DOOR HANDLE ESCUTCHEON PLATE

Jacques Stanitz, Warren, Ohio, assignor, by mesne assignments, to American Radiator & Standard Sanitary Corporation, New York, N. Y., a corporation of Delaware

Application June 11, 1953, Serial No. 25,456

Term of patent 14 years

(Cl. D50—5)

Fig. 1 is a front view of a door handle escutcheon plate, showing my new design;

Fig. 2 is a side elevation of the design shown in Fig. 1; and

Fig. 3 is a perspective view of the new design applied to the bottom corner of a kitchen wall cabinet.

The broken line portions of the drawing disclosure are depicted for illustrative purposes only.

I claim:

The ornamental design for a door handle escutcheon plate, substantially as shown and described.
